Primary Examiner—Stella M. Reid
Assistant Examiner—Elizabeth J Oswecki(57) **CLAIM**

The ornamental design for a neck portion of a bottle, as shown and described.

DESCRIPTION

FIG. 1 is a perspective view a neck portion of a bottle showing our new design;

FIG. 2 is a front elevation view thereof;

FIG. 3 is a right side elevation view thereof, the left side elevation view being a mirror image thereof;

FIG. 4 is a rear elevation view thereof;

FIG. 5 is a top plan view thereof; and,

FIG. 6 is a bottom plan view thereof.

The broken line showing of FIGS. 7-12 is included for the purpose of illustrating only and forms no part of the claimed design.
